C. NESSLER

HAIR WAVING CURLER

Filed Jan. 8, 1926

Patented Aug. 7, 1928.

1,679,488

UNITED STATES PATENT OFFICE.

CHARLES NESSLER, OF NEW YORK, N. Y.

HAIR-WAVING CURLER.

Application filed January 8, 1926. Serial No. 79,959.

My invention relates generally to apparatus used in the processes of waving growing hair on the head, and it has particular reference to the curler or core piece 5 around which the strand or tress of hair is wound before the electric heater is applied thereto.

In some of the apparatus heretofore in use, the curler carrying the wound hair strand has in some cases been locked to the heater, while in other cases the curler has been so securely attached to the heater as to require considerable force and much manipulation to separate the two and these 15 characteristics are most objectionable and in some instances have resulted in the scalp of the subject being badly burned when the emergency has suddenly arisen which demanded a quick separation of the parts 20 in order to remove the heater. By means of my improvements I overcome these drawbacks and provide a curler appliance which has a weak connection with the interior of the electric heater, so that it may be easily 25 and quickly entered therein and removed therefrom, and which provides means for guiding the curler in its passage in and out of the heater and at the same time serves to center the curler with its wound strand 30 within the heater. There are other advantages connected with the use of my improved device which will hereinafter appear from the detailed description thereof.

I have illustrated types of my invention 35 in the accompanying drawings, wherein;

Figure 1, shows a side elevation of an ordinary electric-heater of the tubular type and with my improved device with the wound strand of hair thereon, placed in the 40 heater, and with a scalp-protecting pad mounted around the hair strand between the head-end of the heater and the scalp, which latter is also shown in said figure.

Figure 2, is a side elevation of my improved device shown detached.

Figure 3, is an enlarged side elevation of the friction member or coupling, detached from the curler.

Figure 4, is a side elevation of a modified 50 form of the friction coupling.

Figure 5, is a vertical sectional view of the outer portion of the curler rod with the friction coupling of the modified form mounted therein, and shown on a smaller 55 scale.

Referring to the drawings, 1 is a well

known form of cylindrical hair-curler having a notched member 2, mounted in the inner end for engaging the cord 3, which is tied around the base of the hair-strand 4, 60 before twisting the hair-strand around the curler, as shown in Fig. 1. The forked or notched plug 2, is so arranged that the tubular rod may be turned on its axis in one direction but not in the other, for the 65 purpose of tightening the windings of the hair on the curler, in a manner well known.

In the outer open end of the curler 1, I mount a laterally yielding device 5, which in one form is made from a strip of resilient material, such for example as spring-wire, bent into a pear-shaped loop with its free ends made hook-like and interhooked with each other to close the loop, as shown in Figs. 2 and 3. The hooked end 6, which 75 is disposed to the outside of the interhooking arrangement, conceals the other end 7, and also provides a stout part which is made of a size to fit snugly within the bore of the curler as shown in Fig. 2, by frictional contact, while the tapering wedge-shaped portion 8, bears firmly against the sides of the mouth of the end of the curler rod. This arrangement provides a substantial mounting means for the spring-coupler 80 on the curler to which it may be thus removably attached, though it need not be removed therefrom except for purposes of 85 cleaning or examining the parts.

The greatest width of the spring-loop 5, 90 is such as to make a tight sliding fit with the interior of the heater 9, which is placed over the curler and the wound hair-strand, as shown in Fig. 1. This couples the curler to the heater with sufficient frictional contact to keep the curler in place and at the same time permit of the quick and easy withdrawal of the heater from the engaged curler whenever it becomes necessary to remove the heater in haste.

In Figs. 4 and 5, I show a modified form of the frictional spring coupler in which a resilient wire is bent into a circular loop 5', with one of the ends formed into a helical stem 8', within which lies the other end of the wire. This form is mounted in the end of the curler rod by turning the device like a screw and it provides a very substantial mounting means for the loop on the curler.

From the foregoing it will be readily 110 understood that after the hair-strand 4, is wound around the curler 1, the inner end

of which is anchored to the cord 3, and the hair secured to the curler and wetted in the usual way with an alkaline lotion, the open inner end of the electric-heater is introduced 5 over the outer end of the curler so that the spring-coupler guides the same in its movement and the heater is slid over the curler into the position shown in Fig. 1. The walls of the bore of the heater slightly compress 10 the spring loop 5, laterally and thereby causes it to bear against the walls with considerable spring pressure and couple the curler to the heater. In order to protect the scalp, indicated at 10, from the heat and 15 also from any escaping liquid from the heater, I surround the strand of hair 4, with one of my improved forms of protective pads 11, which comes between the inner end of 20 the heater and the scalp, as shown in Fig. 1. It will be noted that the spring loop 5, also serves to center the hair curler 1, with 25 its wound tress 4, within the bore of the heater and this is an important advantage over other forms of curlers, in that it keeps the hair-strand from shifting to one side and lying against the wall of the hot heater and thereby becoming overheated or burned. 30 The improved construction affords quick and easy assembling of the parts of the apparatus for the permanent hair-waving process, and what is of great importance is that the heater and curler may be instantaneously separated in the case of any emergency, such as overheating of the apparatus. 35 The form of curler herein shown is that of my Patent No. 1,105,595, granted July 28, 1914, but of course any curler device or core-piece for carrying the wound hair may be employed. It will also be understood that 40 the friction coupler 5, may assume any desired form and need not be that of a loop, as shown, the essential feature being that this device which is applied to the outer part of the curler should have the function and 45 capacity of engaging the interior of the heater tube with a frictional sliding contact, as described. Furthermore, this member 5, may be made of any suitable durable material which will serve to undergo slight 50 lateral compression when entered in the heater and then to expand or resume normal condition when withdrawn.

Having thus described my invention, what I claim and desire to secure by Letters Patent, is:—

1. A curler for permanent hair waving, comprising a rod around which a tress of hair may be wound for insertion in a heater, the said rod having mounted thereon a laterally compressible yielding member insert-

able with said rod and adapted to engage frictionally the interior of the heater and placed under tension thereby.

2. A curler for permanent hair waving, comprising a rod around which a tress of hair may be wound for insertion in a tubular heater, the said rod having mounted thereon at its outer end a laterally yielding resilient device for engaging the interior of the heater with sliding tensional contact and serving to center the curler in the heater.

3. A hair-curler adapted to be inserted in a tubular heater and having its outer end provided with a resilient looped device for lateral engagement with the sides of the interior of the heater.

4. A hair-curler adapted to be inserted in a tubular heater and having its outer end provided with a resilient looped device for engaging the heater and comprising a piece 80 of wire bent on itself with its free ends brought together to provide a stem for attachment to the curler.

5. In apparatus for waving hair, a rod 85 around which a strand of hair may be wound for insertion in a heater, and a device comprising laterally projecting resilient members adapted to be detachably connected with said rod and to engage the interior wall of the heater with yielding pressure when inserted therein and thereby retain the rod in operative position and permit easy removal of said rod.

6. In apparatus for waving hair, a rod 95 around which a strand of hair may be coiled for insertion in a heater, the said rod having its outer end provided with a recess, and a device removably inserted in the recess of the rod and adapted to engage the interior of the heater with resilient pressure when inserted therein and thereby retain the rod in operative position and permit easy removal of said rod.

7. In apparatus for waving hair, a rod 105 around which a strand of hair may be wound for insertion in a heater, the said rod being provided with a recess, and a device formed of resilient material and removably inserted in the recess in said rod and engaging the walls thereof with spring pressure, the outer end of said device being adapted to engage the wall of the interior of said heater with spring pressure when inserted therein and thereby retain the rod in operative position and permit easy removal of 110 said rod.

In testimony whereof, I have hereunto signed my name to this specification on the 6th day of January, 1926.

CHARLES NESSLER.
